(57) CLAIM

The ornamental design for a garment bottom, as shown and described.

DESCRIPTION

FIG. 1 is a rear perspective view of a garment bottom showing our new design;

FIG. 2 is front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a partial enlarged detailed front view with a portion of the front of the garment bottom removed showing the interior rear of the waistband.

The broken dashed lines shown in the drawings illustrate portions of the garment bottom that form no part of the claimed design. The broken dot-dashed line, which defines the bounds of the claimed design, forms no part thereof.
